RADIO AMPLIFIER

Application filed April 18, 1930. Serial No. 445,291.

My invention relates to radio-receiving circuits, more particularly to certain features therein whereby improved operating characteristics may be obtained.

5 In present-day practice, because of the necessity of imparting the desired characteristic of selectivity to radio-receiving circuits, the primary windings on the radio-frequency transformers are designed with a minimum 10 number of turns, and the loss in energy-transfer occasioned thereby is usually compensated by some form of regeneration.

A system of the above type will usually cause either excessive amplification at the 15 high frequencies, or insufficient amplification at the low frequencies, depending upon the constants of the circuit, thereby giving the circuit a poor response-curve characteristic.

In the same type of system employing a 20 comparatively few turns on the primaries of the radio-frequency transformers, the problem of stabilizing the operation of the circuits by the well-known means of cancelling plate-grid feed-back through the use of neutralizing condensers becomes more difficult, as it very often happens that, when the point 25 of balance is reached for broadcast frequencies, oscillations will occur at the higher frequencies, particularly those frequencies at 30 which parasitic oscillations are prone to develop.

Accordingly, it is one object of my invention to provide a circuit, the frequency response curve of which is substantially uniform over the broadcast range of frequencies.

Another object of my invention is to provide means for increasing the range of neutralization in the direction of the higher frequencies.

40 A further object of my invention is to provide means whereby a neutralizing means in radio circuit may be utilized for regenerative purposes.

45 A further object of my invention is to provide means whereby audio-frequency noises developed in the high-frequency circuits will not be transmitted to the audio-frequency stages.

The means for accomplishing the above 50 objects of my invention is disclosed in the

accompanying drawing, the single figure of which is a diagram illustrating my improved receiving circuit, an explanation of which follows.

The system comprises a plurality of stages 55 of radio and audio-frequency amplification, the last stage of audio being a push-pull arrangement. My invention, however, may be used in various modified circuits, as will appear more apparent as the specific improvements are pointed out in detail.

An antenna circuit 1 is shown coupled, both inductively and conductively, to the input circuit 3 of the first radio-frequency stage, the output or plate circuit of which 65 comprises a pair of coils 5 and 7, bridged by a resistor 9, the connection to one of said coils being variable.

The resistor 9 functions as a potentiometer means for controlling the input to the coil. 70 To prevent undesirable changes in the plate potential of the first radio-frequency tube, when the variable contact on the control resistor 9 is shifted, I insert the coil 5, as described above, this coil serving as a radio-frequency choke in the output circuit, but, at the same time, providing a relatively low-resistance path for the direct current in the plate circuit.

The above coil 7 is inductively coupled to 80 the input circuit 11 of the second radio-frequency stage and, in similar manner, the output circuit 13 of this stage is inductively coupled to the input circuit 15 of a third radio-frequency stage of amplification.

85 Neutralization is provided in the three radio-frequency amplifiers referred to above, the particular method resorted to, for purpose of illustration, is the Rice system, utilizing capacities 17, 19, 21 in series with their respective feed-back reactors 23, 25, and 27, between the anodes and the lower ends of the input circuits of their respective amplifiers.

I have found that, by inserting a capacity 90 of approximately .0001 microfarad in one of the radio-frequency stages (preferably the second amplifier) between the cathode 31 and the plate circuit 13, as shown, together with a resistor 33 of approximately 5000 ohms in the plate circuit of the same amplifier, a 100

marked increase in the range of effective neutralization is obtained. The circuits become more stable than heretofore at the higher frequencies at which parasitic oscillations are prone to develop. The presence of the condenser in the circuit, as shown, renders the plate circuit a capacitative load on the tube, thus causing a degenerative feed back through the grid-plate capacity to counteract any tendency of parasitic oscillations to develop.

Not only have the above desirable results been obtained by the use of the capacity 29 and the resistor 33 but I have found, in addition, that the neutralizing condenser 21 of the third amplifier, in conjunction with its corresponding feed-back coil 27, functions as a regenerative feed-back circuit to further amplify the incoming signals.

20 In combination with the above, I have provided, in the output circuit of the last radio frequency amplifier, a novel circuit arrangement which constitutes the coupling means between said amplifier and the detector stage. 25 This coupling between said amplifier and said detector comprises a resistor 35 of approximately 10,000-50,000 ohms in parallel with a choke coil 37 of high L/C ratio, with dimensions of approximately .002 henries and 30 low distributive capacity. Condensers 39 and 41 are inserted in the plate-grid connection between the resistor 35 and the choke 37 and between the choke 37 and the grid 43, as illustrated, said grid being grounded through 35 a high-resistance grid leak 45. Condenser 39 is not critical, any value from 200-5,000 micro-microfarads being sufficient while condenser 41 should have a value of approximately 250 micro-microfarads, as it serves in 40 the capacity of grid-leak condenser for the detector tube.

The elements comprising the above coupling and arranged as described, favor the lower frequencies of the broadcast range, particularly by reason of a resonant condition existing between the choke, the plate-filament capacity of the preceding radio frequency tube, the grid-filament capacity of the detector and the various stray capacities in the 45 coupling, whereby a low-frequency peak is produced. This coupling, without the condenser 29 and resistor 33 arrangement described above, is sufficient to stabilize the circuit at the higher frequencies, in which case, 50 the neutralizing circuit involving the neutralizing condenser 21 will continue to act as a regenerative circuit.

It is believed that the above stabilizing effect at the frequencies above the broadcast 60 range is a result of the distributed capacity of the choke acting as a balancing or neutralizing condenser at those frequencies in the radio frequency amplifier in which it is located.

65 However, the best results are obtained in

the neutralizing effect with the combination of the two arrangements in the same system, as they appear to exert some influence upon each other to promote a greater degree of stabilization of the circuits.

70 Additional beneficial results are obtained from the above described coupling. Because of its favoring the lower radio frequencies, it either completely or partially flattens the response curve, in that the high frequencies, 75 which might have been over-amplified through the first two radio frequency stages are now under-amplified through the third radio frequency amplifier. As might otherwise be expressed, the low-frequency currents 80 which might have been under-amplified in the first stages, are over-amplified in the last stages, whereby a substantially flat characteristic response curve may be obtained.

85 In addition to the above, it has been found much easier to isolate a fixed-coupling arrangement, as described, than the ordinary tuned-transformer coupling, with the consequent result that overall feed-back and audio pick-up are reduced or entirely eliminated, 90 thereby further increasing the stability of the system.

A plurality of fixed couplings of the type described above may be used in a multi-stage circuit to advantage, where the ratio of the 95 responses at high and low radio frequencies make this arrangement desirable.

99 In a receiver employing a fixed coupling, as disclosed by me, ahead of the detector tube, as shown, if the choke 37 were omitted or if the resistor 35 were replaced by the choke, then variations in B. voltage, arising from poor regulation at the source or induced low-frequency currents in the output circuit, 100 would be fed directly to the grid 43 of the detector tube, resulting in a "flutter" or audio-frequency tone. With the choke connected as shown, those low audio-frequency noises or tones are by-passed and fail to reach the grid of the detector tube, thereby preventing the disagreeable results outlined above. The above assumed changes, it will be noted, produce the ordinary resistance and impedance couplings well known in the art, 110 in view of which it might be said that my coupling, in addition to its other features, 115 comprises a new and useful improvement over prior well known coupling arrangements.

120 The detector tube output comprises the primary of an audio-frequency transformer which is preceded by a low-pass filter comprising radio frequency choke 47 and capacities 49 and 51 for radio-frequency-current components existing in the output circuit of 125 the detector.

130 The secondary of the transformer constitutes the input circuit of the first audio-amplifier designated by the reference numeral 53, the output of which is amplified

through a stage of push-pull designated, as a whole, by numeral 55.

Potentials for the various circuits may be supplied from any convenient well known source, such as the rectifying and filtering system 57 disclosed by me, and may be applied to a voltage divider comprising the resistor 59 from which desired B-potentials may be tapped. An independent coil 61 is provided 10 as a source of alternating-current supply to the heaters of the radio frequency detector and first audio tubes all of which are preferably of the alternating current type, although direct current tubes may be used in 15 lieu thereof. Another coil 63 is disclosed as providing alternating current for the filaments of the tubes used in the push-pull stage which are preferably of the power type; e. g. UX 171. The resistors 65, 67 and 69 20 constitute means for impressing a desirable negative grid bias on the radio frequency tubes, the first audio and the power tubes, respectively. Suitable capacities are provided for by-passing the various potentials.

25 Thus, I have disclosed, in detail, a radio-receiving system capable of functioning to attain the objects of my invention. Various modifications may be made, such as shifting the various features of my invention to any 30 of the other stages of the system or utilizing them in analogous circuits, without departing from the scope of my invention, and I, therefore, do not desire to be limited to the specific details disclosed except in so 35 far as is necessitated by the prior art and the appended claims.

I claim as my invention:

1. A high-frequency circuit comprising amplifying means and a detector, means in combination with said circuit for neutralizing feed-back within the broadcast range of frequencies, and means, for increasing the frequency range of neutralization of said circuit, said means comprising the combination of a capacitative load on said amplifying means and a fixed resistance-choke coupling between said amplifying means and said detector. 75

2. A high-frequency circuit comprising a plurality of amplifying stages, a detector stage, means in combination with said circuit for neutralizing undesirable feed-back at broadcast frequencies, and means for increasing the frequency range of neutralization in said circuit comprising the combination of a capacitative load in the output circuit of one of said amplifying stages and a resistance-choke coupling between certain of said stages. 80 85

3. A high-frequency circuit comprising a thermionic device having an input and an output circuit associated therewith, means cooperating therewith for neutralizing feed-back in said circuits at broadcast frequencies, said output circuit comprising coupling means of low distributive capacity for extending the range of neutralization above that of the broadcast range. 90 95
